E. C. STUMME.

COIN SORTER.

APPLICATION FILED DEC. 22, 1919.

Patented May 3, 1921.

UNITED STATES PATENT OFFICE.

EMIL C. STUMME, OF READLYN, IOWA.

COIN-SORTER.

1,376,904.

Specification of Letters Patent.

Patented May 3, 1921.

Application filed December 22, 1919. Serial No. 346,640.

To all whom it may concern:

Be it known that I, EMIL C. STUMME, a citizen of the United States, residing at Readlyn, in the county of Bremer, State of Iowa, have invented certain new and useful improvements in Coin-Sorters; and I do hereby declare the following to be a full, clear, and exact description of the invention, such as will enable others skilled in the art 10 to which it appertains to make and use the same.

This invention relates to coin handling, and more especially to assorters; and the object of the same is to produce a simple 15 machine by means of which a mass of different coins can be sorted quickly, assembling those of each size in their own hopper, and stacking them flat in an upright pile therein from which they can be taken 20 at will and counted.

The invention is designed for the use of cashiers who are called upon to handle coins in large numbers, and an important feature is its extreme simplicity which reduces the 25 cost of manufacture and puts the device within the reach of all.

The following specification sets forth one practical adaptation of the principle, reference being had to the drawings wherein:

30 Figure 1 is a front elevation.

Fig. 2 is a cross section taken through the tray and the hopper for the smallest coins.

Fig. 3 is a fragmental plan view.

Fig. 4 is a plan view of the delivery 35 strip.

Rising from a base 1 are standards 2 forked at their upper ends, the rear fork-arms 3 carrying an upright plate or board 4 and above it a rear strip 5, and the for- 40 ward fork-arms 6 carrying a front strip 7 spaced slightly from the rear strip to form a channel for the coins as best seen in Fig. 2. At one end of the machine the rear strip 5 carries a tray 8 onto which the coins to be 45 handled are poured, and opposite the lower end of the tray the other strip may carry a baffle plate 9 to prevent the coins falling over this strip if they slide down the inclined tray too rapidly. The parts thus far- 50 described may be given any appropriate size and shape, and of course the operator may stand in any position with reference to the machine but we will assume that he stands in front of it as it appears in Fig. 1, the 55 tray then being at his left hand and

the crank handle (described below) within reach of his right hand.

The fork-arms 3 and 6 preferably have bows 13 and 16 just beneath the strips 5 and 7, these bows forming guides for and receiv- 60 ing the upper run of a carrier which comprises two chains 10 connected at intervals by cross bars 11, the same constituting an endless belt moving over a pulley or pulleys 12 at one end and 14 at the other end of the 65 device; and this carrier is somewhat loose so that its lower run may hang and travel on edge behind the rear fork arms 3 as seen in Fig. 2. One pulley has a crank handle 15, and when it is turned the upper run of the 70 carrier will move to the right as seen in Fig. 1, and its cross bars should be so spaced that they will carry the coins along within the channel between the strips 5 and 7. Beneath this run is a grid which may well be 75 made up of a rod 17 standing parallel with the board 4 and supported therefrom by occasional braces 18, and a number of cross rods or bars 19 leading from the rod 17 back to and extending a slight distance into the 80 board 4. These bars are variously spaced. For a distance at the left end of the machine they are spaced sufficient to permit the smallest coin (a dime) to drop between them, the next group of bars are spaced to permit a 85 penny to pass through, the next group will drop nickels, then quarters, halves, and dollars. With this construction it is clear that as miscellaneous coins run down the tray into the channel, they fall into and are car- 90 ried along to the right by a carrier whose cross bars move them or roll them along the grid and over its rods or bars 19. In the first or left hand group these bars are spaced so closely that no coins can fall through but 95 the dimes, and therefore they are picked out of the mass and all other coins are carried along; and thus the separation of coins takes place throughout the length of the channel, the dollars being carried to the extreme 100 right.

Carried by the framework, and possibly supported entirely from the board 4, are several hoppers 20, each having its wide open end underlying one of the groups in said 105 grid so that it will receive only the coins picked out of the mass as already described. The walls of the hopper converge downward as perhaps best seen in Figs. 1 and 2, to a spout 21 which is a pendant tube of a size 110

to contain the appropriate coin, the tube being preferably slotted as at 22 down its front as seen. At its lower end the tube carries a flattened sleeve 23 within which is movably mounted a delivery strip 24 which may be rigid or flexible and of any appropriate material and length, its body provided with openings 25 of a size to receive the appropriate coin, although by preference these 10 openings are slightly oval along the length of the strip as seen in Fig. 4. Said strip has stops 26 and 27 at its front and rear ends to prevent it from being drawn through and out of the sleeve 23, and beyond either stop 15 it may well have a handle 28. With this construction, let us assume that each strip has ten openings in it, and it stands pushed to the rear through the sleeve so that its front stops 26 abut the same. Let us assume 20 that we are considering the left hand hopper 20, whose spout 21 will by preference be longer than that of any other hopper if dimes be the most popular coins handled. As the dimes are picked out of the mass and 25 delivered into the hopper, they accumulate within its spout where they lie horizontally or face to face, and the lowermost drops into the front opening 25 in the strip, which opening registers with the spout when the 30 strip stands in normal position. Now when the operator grasps the handle 28 and draws the strip forward through the sleeve, ten dimes are taken from the hopper and delivered successively by the spout into the openings 25; and as the strip moves forward through the sleeve, each dime is dropped out of its opening into the operator's hand or into a receptacle or onto the base 1. The 35 reverse movement of the strip to the rear would discharge or deliver ten more dimes, and thus each complete movement of the strip automatically counts the coins delivered. I might add that there should be one more opening in the strip than the total 40 number counted, so that when it comes to rest in either extreme position the endmost opening receives a coin for the subsequent delivery stroke.

From this description it will be gathered 50 that the coins are thrown upon or poured onto the tray in a mass, the inclination of the tray and the shape of the channel between the strips 5 and 7 causes the coins to be assorted while they are standing on edge, al- 55 though it is possible that two or three thin coins might stand on edge in this channel, whereas thicker coins like the dollar would be handled one by one. The coins stand edgewise within the carrier and drop edge- 60 wise through the openings within the grid; they fall edgewise into the hopper and by its shape they are turned to a horizontal and stacked flat within its spout, and the delivery mechanism handles them in this horizon- 65 tal position. Therefore, of course, each strip

24 should correspond in thickness with that of the coin it is to deliver. It will be clear that the strip could be flexible, with handles at both ends, and moved in opposite directions by one or two operators, or it could be 70 a stiff strip pulled in one direction and pushed in the other.

What is claimed is:

1. In a machine of the class described, the combination with a horizontal trough, a grid 75 fixed along its bottom and whose cross bars are variously spaced in groups throughout its length, and a series of receptacles beneath the grid, each having a hopper of a length to underlie one of said groups and a pendant tube in which are stacked the coins dropped into the hopper; of means for feeding mixed coins to that end of the trough beneath which the grid openings are smallest, the trough being of a width to hold said coins on edge, 80 and means moved mechanically above the grid for carrying along the trough those coins not dropped through its openings.

2. In a machine of the class described, the combination with a trough, a grid along its 90 bottom whose cross bars are variously spaced in groups throughout its length, receptacles beneath the individual groups, and coin delivery mechanism for each receptacle; of means for feeding mixed coins in mass to 95 one end of said trough, and means for moving them along the same over the grid, as described.

3. In a coin sorter, the combination with 100 parallel strips spaced to form a channel, means for supporting them, a grid carried by the supporting means beneath said strips and having its cross bar variously spaced in groups throughout its length and receptacles beneath the several groups; of guides 105 within said support and an endless carrier movable over the grid between it and the strips toward the end of the widest spacing of the grid bars.

4. In a coin assorter, the combination with 110 parallel strips spaced to form a channel, means for supporting them, a grid carried by the supporting means beneath said strips and having its cross bars variously spaced in groups throughout its length, and receptacles 115 beneath the several groups; of guides within said support, a carrier consisting of endless belts movable within said guides and cross bars connecting them and spaced to receive the largest coins handled, and pulleys and 120 operating mechanism for supporting the said carrier and moving its upper stretch above the grid from the end of its narrowest spacing toward and over the other end.

In testimony whereof, I affix my signature, in the presence of two witnesses.

EMIL C. STUMME.
